[57] **CLAIM**

The ornamental design for a display device for placement on a refrigerator, as shown and described.

DESCRIPTION

FIG. 1 is a perspective view of a display device for placement on a refrigerator showing my new design;
FIG. 2 is a front elevation thereof; the rear elevation being a mirror image thereof;
FIG. 3 is a left side elevation thereof; the right side elevation being identical;
FIG. 4 is a top plan view thereof; and,
FIG. 5 is a bottom plan view thereof.
The broken lines showing of the refrigerator in FIGS. 1-3, and 5 is for illustrative purposes only and form no part of the claimed design.

1 Claim, 4 Drawing Sheets

FIG. 2

FIG. 4

FIG. 3

FIG. 5
